UNITED STATES PATENT OFFICE.

FRANK W. LODER, OF POUGHKEEPSIE, NEW YORK.

SHOE-LACE FASTENER.

SPECIFICATION forming part of Letters Patent No. 576,761, dated February 9, 1897.

Application filed January 6, 1896. Serial No. 574,435. (No model.)

To all whom it may concern:

Be it known that I, FRANK W. LODER, a citizen of the United States, and a resident of Poughkeepsie, in the county of Dutchess and State of New York, have invented certain new and useful Improvements in Shoe-Lace Fasteners, of which the following is a specification, reference being had to the accompanying drawings, forming a part thereof, in which 5 similar letters of reference indicate corresponding parts.

This invention relates to fastening devices for shoes, and to that class thereof which are known as "lace-shoes;" and the object of the 15 invention is to provide a simple and effective device which may be secured to the shoe at the top thereof, and to which the end of the shoe-laces may be easily and quickly connected in such manner as to hold them securely in place, thus avoiding the necessity 20 of tying the same.

The invention is fully disclosed in the following specification, of which the accompanying drawings form a part, in which—

25 Figure 1 is a perspective view of a shoe provided with my improvement; Fig. 2, a perspective view of the improvement or fastening device detached, and Fig. 3 a modification.

In the drawings forming part of this application, A represents an ordinary lace-shoe provided with the usual eyelets B and hooks B², and the shoe is laced in the usual manner, the lace or string being shown at E; and in 35 the practice of my invention I provide a fastening device which is adapted to be secured at each side of the fly of the shoe and at the top thereof, and which comprises a single piece of metal which may be cut from a piece of sheet metal, and which comprises a central portion or head D, side arms or projections d, by means of which the fastening device is 40 secured to the shoe, and additional arms or projections d² and d³, which project in line with each other and at right angles to the projection d, and formed centrally of the 45 head D is a hook d⁴, which is similar in form to the usual button-hook.

The operation will be readily understood from the foregoing description when taken in 50 connection with the accompanying drawings.

The fastening device is secured, as herein-before stated, to each of the flies of the shoe at the upper parts thereof by inserting the side projections d through the shoe or the material thereof and bending the same inwardly, as shown in Fig. 1, and when thus secured in position the arms or projections d² and d³ will extend backwardly, and the end of the shoe-lace is passed once around the hook d⁴ and then between the arms or projections d² and d³ and upwardly between the arm or projection d² and the material of the shoe. 55

The upper side of the arm or projection d² is rolled or curved, as shown at d⁵, in order to 60 increase the friction, and the outer end of said arm or projection is also curved outwardly in order to facilitate the hereinbefore-described operation, and in the construction shown in Fig. 3 the arms d² and d³ project 65 forwardly instead of backwardly, as shown in Fig. 1. It will thus be seen that I accomplish the object of my invention by means of a device which is simple in construction and which is comparatively inexpensive, and 70 which will also securely hold the ends of the shoe laces or strings, and thus avoid the necessity of tying the same, or the frequent retying thereof, which is usually necessary when this means of fastening is resorted to. 80

Having fully described my invention, I claim as new and desire to secure by Letters Patent—

The combination with the upper of a shoe, of a shoe-lace fastener, consisting of a metal 85 plate formed as shown with a head D, having side arms d for securing the fastener to a shoe, and central hook d⁴, and parallel arms d² and d³ projected at right angles to the side arms, all the parts integral with the plate 90 and constructed substantially as shown and described.

In testimony that I claim the foregoing as my invention I have signed my name, in presence of the subscribing witnesses, this 21st 95 day of December, 1895.

FRANK W. LODER.
